UNITED STATES PATENT OFFICE.

BEN I. DILGER, OF BIRMINGHAM, ALABAMA.

GRAVE COVERING.

Application filed December 27, 1920. Serial No. 433,165.

To all whom it may concern:

Be it known that I, BEN I. DILGER, a citizen of the United States of America, residing at Birmingham, in the county of Jefferson and State of Alabama, have invented certain new and useful Improvements in Grave Coverings, of which the following is a specification.

My invention relates to a reinforced concrete structure forming a permanent and pleasing covering for a grave, which can be produced economically, is comparatively light, and can be shipped nested so as to reduce transportation costs.

At the present time, so far as I am aware, there is no practical grave covering in use other than stone slabs or monuments and these are not only expensive in themselves but require an expensive foundation, great care and cost in transporting and the use of skilled workmanship to set them. For these reasons, at the present time there is available no practicable comparatively inexpensive grave covering of a permanent and durable nature.

According to my invention I utilize a metallic frame carrying a wire mesh covering on which is applied a coat of cement, and the cement before it hardens is given a surface covering of marble chips or pieces of fine ornamental stone which will give to the finished composite article the appearance of an arched stone covering. Such a grave covering is light, inexpensive to handle, and easy to set in position over the grave mound as the metallic frame carries spuds or anchor points which, when forced into the ground, will hold the covering in place.

A further distinctive feature of my invention relates to the manner of attachment of the name plate and it contemplates so mounting the name plate to the structure that it is detachable, thus permitting the covering to be marketed with the name plates blank and permitting the plate alone to be removed for initial marking or for any required change in marking or additional marking. This is of frequent occurrence and can be accomplished without disturbing the covering by the simple removal and replacement of the name plate.

My invention will be best understood by reference to the accompanying drawings

which illustrate the same in its preferred embodiment only, and in which:—

55

Fig. 1 is a plan view of the metallic frame with the wire mesh covering and marker plate attached.

Fig. 2 is a partial plan view showing in part the cement coating and in part the marble chip covered surface of the grave covering.

Fig. 3 is a side view of the complete structure; and

Fig. 4 is a side view of one end of the structure, the cementitious coverings being broken away successively.

Fig. 5 is an end view of Fig. 3; and

Fig. 6 is a perspective view of the iron frame work with the wire mesh covering removed.

Similar reference numerals refer to similar parts throughout the drawings.

As my invention is manufactured, I first construct a metal frame work such as is illustrated in Fig. 6, wherein it will be seen that I provide similar arched angle iron end pieces 1 having their horizontal flanges inverted towards each other and cross connected near their center by parallel spacer bars 2 and near each end by angle irons 3. Beyond the angle irons the tips of the end members 1 are downturned and sharpened to form anchor spuds or points 4. Over the frame as thus manufactured I apply a covering of wire mesh 5, such as galvanized hardware cloth, or any suitable reinforcement and support for the cement coat, and I fasten its edges by means of bolts 6 to both angle irons 3 and if desired to the end frames. To the bars 2 near the head end of the frame work I bolt or otherwise suitably attach a name plate 7 having a thickness which will cause it to project above the covering to be applied to the metallic frame work as thus far described. Over the wire mesh I apply a layer of cement 8 and before this hardens I cover it with a coating of chipped marble 9 or any suitable granular or fragmental stone which will conceal the cement and give the composite article the appearance of stone. The article as thus manufactured rapidly dries and hardens and becomes a reinforced monolith, possessing great strength and durability and which, therefore, can be nested and transported at

90

comparatively small cost. It is adapted to be readily applied to cover a grave mound 10 by merely pressing down the spuds or tips 4 into the ground. Preferably the end 5 members 1 have their vertical flanges out-turned and these flanges project slightly above the concrete and stone covering applied to the frame so as to better protect the latter from damage in shipment and 10 handling. The side edges of the name plate are vertical, thus permitting it to be removed from the countersunk seat provided for it in the monolithic structure and to have original, changed or additional marking applied thereto, after which the name plate can be replaced in its seat and bolted or otherwise attached to the structure. It is preferable to bolt the name plate to the frame work, the top bars 2 where exposed 20 in passing the name plate seat being provided with bolt or screw holes to receive the attaching elements. The name plate can be attached by any suitable fastenings of a permanent and non-rustable nature which 25 will provide the covering with a suitable means for properly marking the grave.

I desire it to be understood that the metallic frame work may be made up out of any suitable material and in any shape 30 and size to suit the taste of different people. Also the surface coating may be of marble chips or other stone, but marble or granite chips are preferred as they are in large 35 quantities at all monument yards and are of practically no value, while as thus applied to the grave covers they will give them a most pleasing appearance. I prefer to leave the ends of the arched grave cover open but this is not essential.

40 My invention is not intended to be restricted in scope to the specific embodiments shown, but contemplates such modifications as come within the spirit and scope of the claims.

45 Having thus described my invention, what I claim as new and desire to secure by Letters Patent, is:—

1. A grave cover comprising a metallic skeleton frame work, a wire mesh covering 50 over the frame work, a cementitious coat applied over the wire mesh and comprising exposed particles of stone suitable for a monument to form a light hollow reinforced monolithic structure of an ornamental nature.

55 2. A grave cover comprising a light arched skeleton metallic frame work covered with wire mesh attached thereto, a coating of cement applied over the wire mesh to form 60 a light hollow reinforced monolithic structure, said cement coating having an outer surface coating of fragmental stone, suitable

for monuments embedded in and covering the cement, and a countersunk seat for a name plate, and means to detachably connect 65 a name plate to said structure.

3. A grave cover comprising a metallic frame work, an inner layer of cement thereon to form a reinforced monolithic structure, an outer surface coating of fragmental 70 stone suitable for monuments embedded in the cement, a detachable name plate, and means to attach same to the metallic frame work.

4. A grave covering comprising an elongated metallic frame work comprising arched end members, longitudinal connecting members, a wire mesh layer applied over said frame work, a name plate attached to the longitudinal members above the wire 80 mesh, a coating of cement applied to the wire mesh and having a surface coating of monumental stone chips embedded in the cement coating before it hardens, said cement and stone coating leaving the name plate exposed. 85

5. A grave covering comprising an elongated metallic frame work comprising arched end members, longitudinal connecting members, a wire mesh layer applied over 90 said frame work, a name plate attached to the longitudinal members above the wire layer, a coating of cement applied to the wire mesh, and a surfacing of marble chips applied to and embedded in the cement coating before it hardens, said cement and marble chips leaving the name plate exposed, said name plate being adapted to be detached and lifted out of its seat in the coating of cement, 95 as and for the purposes described. 100

6. A grave cover formed of an oblong arched reinforced monolithic structure having metallic anchoring projections at its ends and having a countersunk seat and a name plate detachably anchored in position in 105 said seat.

7. A grave cover formed of an oblong arched monolithic structure having a skeleton reinforcing frame carrying arched studs projecting downwardly from the corners of 110 the structure, said monolithic structure being formed with a countersunk seat for the reception of a name plate, a part of said metallic skeleton frame work underlying said seat, a name plate detachably mounted in 115 said seat, means to connect the name plate to the underlying frame work element, and monumental stone fragments embedded in and covering the outer surface of the monolithic structure. 120

In testimony whereof I affix my signature.
BEN I. DILGER.
